WASHING MACHINE BASKET

Otto T. Dehle, Long Island City, N. Y.

Application February 6, 1937, Serial No. 124,387

7 Claims. (Cl. 68—197)

This invention relates to improvements in washing machine baskets and has for its object the provision of a basket adapted to fit within the tub of a washing machine, such, for example, as that shown in U. S. Patent 1,775,554, dated September 9, 1930. Such machines as described in said patent wash clothes solely by a vigorous and rapid movement of soapy water in a tank. This is accomplished by providing a suitable pump which forces water into the tub through a plurality of jets or streams, said pump withdrawing the water from the tub via a return pipe to the suction side of the pump. The incoming streams agitate the clothes in the tub until thoroughly washed, in the manner described in the aforesaid patent, the clothes occupying practically the entire area inside the tub, no mechanical paddles or agitators being used.

One of the problems present with this type of washer is to prevent the clothes from clogging the return pipe; another is to easily and quickly fill and empty the tub with clothes. Also, it is difficult to drain the clothes when they are removed piecemeal from the tub.

The present invention eliminates these difficulties and others, as will be apparent from the following specification which also refers briefly to further objects and advantages of the invention which is particularly adapted for use in laundries where large machines are used and large quantities of clothes are washed in a batch. By way of illustration the invention is described as applied to a basket for use with the washing machine described in the aforesaid patent, but it will be obvious the invention can be used with any other suitable type of washer.

In the accompanying drawings:

Figure 1 is a sectional view on the line 1—1, Figure 3, of a basket constituting this invention; Figure 2 is a sectional view on the line 2—2 of Figure 1;

Figure 3 is a front elevation of the basket, Figure 1;

Figure 4 is a side view of the basket, Figure 1;

Figure 5 is a perspective view of the basket, Figure 1, in the tub of a washing machine showing its relation to the water pipes therein, the tub T being shown in dot-and-dash lines to permit the parts therein to be clearly seen;

Figure 6 is an enlarged view of the manifolds on the basket shown in the preceding figures;

Figure 7 is a view of the inside wall of the basket, Figure 1, showing drain holes opening into the manifolds;

Figure 8 is a sectional view on the line 8—8,

Figure 4, showing fixed and sliding guides on the ends of the basket; and

Figure 9 is a view, partly in elevation, showing the guides and sliding shoes on the ends of the basket.

In Figure 1 the numeral 10 denotes the inner lining or wall of the basket constituting the bottom ends and sides thereof. This is as smooth as possible inside. The top of the basket is open although it may be closed with a suitable cover if desired. This inner wall is preferably made of metal, and the bottom is perforated with small holes indicated at 11 which permit water to flow from the interior of the basket down into the spaces 12 below the bottom thereof. The bottom is braced by a plurality of laterally extending ribs 13, as shown.

The side and end walls are perforated as just described, these holes being arranged in vertical columns as indicated at 14, Figure 2, and opening into the interior 15 of the U-shaped manifolds 16. These manifolds are arranged vertically and spaced as shown in the drawings and are made of light brass or the same metal as the wall 10. The entire basket is constructed in any suitable manner and bolted or welded together, the exact details of construction being immaterial to the carrying out of the invention.

The front of the basket is hinged at 17, 18 to permit the front to be swung outwardly as shown in dotted lines, Figure 1, to permit of easily loading and unloading the basket. A hasp or other suitable fastening (not shown) is provided to keep the front normally closed when the basket is in use.

All the manifolds are open at the bottom to permit free drainage of water from the drainage spaces 15 therein. The outer walls of the manifolds 16, as shown at 19, are solid, which prevents water running out of the basket through the sides thereof when the basket is lifted out of the tub. The water can only run into the spaces 15 within the manifolds and is conducted thereby to the bottoms 20 thereof.

A plurality of relatively large apertures 21 are made in the bottom of the basket, and similar apertures 22 are made along the back. Another row of apertures is made at 24 in the front. Slots 23 may extend down the front from the upper edge of the basket. These holes and slots permit the streams of water in the washing machine tub to agitate the clothes in the basket and together with the holes 11 permit the washing operation to be properly performed.

The arrangement of the large and small holes 55

and slots as just described is important as the proper flow of water in a washing machine of the type referred to, or any water-jet type, must not be impeded. Heretofore, for this reason, only 5 open-mesh baskets have been employed, as, until the present invention, no way was known to employ a basket of relatively solid construction without so seriously impeding the water flow as to render the use of the basket impractical. Such 10 open baskets have the further disadvantage that clothes become tangled in the open meshes, or wad together so they do not wash. By the improved construction here shown, the clothes do not tangle as the interior of the basket is comparatively smooth. The clothes do not wad as the water streams are not impeded and the clothes cannot collect in front of the return or draw-off pipe. The basket structure is rigid and two hundred to three hundred pounds of clothes 15 can be handled therein at a wash. The removal of sludge is facilitated and the general efficiency of the washing machine is increased.

Reference to the aforesaid patent will disclose a washing machine in which there are three 20 streams of water going into the tub, the return or draw-off pipe taking water from the top of the tub and returning it to the pump.

In Figure 5 of the instant application, instead of three streams of water in the tub, four may be 25 employed, but the operation is the same as that described in the aforesaid patent. In the aforesaid figure, there is a perforated manifold 21a which discharges streams of water upwardly through the apertures 21 in the bottom of the basket. A second manifold 22a discharges horizontal jets of water through the apertures 22 in the back of the basket. Another manifold 23a discharges water at an angle downwardly 30 through the slots 23 in the front of the basket, these angular jets of water corresponding in respect to their general direction and action to the oblique opening 41 shown in the aforesaid patent.

Another set of jets or streams from the pipe 24a enter the basket horizontally through the 45 apertures 24 in the front thereof.

It will be seen from the foregoing that there is a series of vertical streams of water impinging on the clothes in the basket through the holes 21 in the bottom thereof and two horizontal sets of 50 jets, one entering through the holes 22 in the rear and holes 24 in the front respectively which jets tend to give the clothes a rotary motion, and that in addition, there are the downwardly directed streams or jets that enter the basket 55 through the slots 23 in the upper part of the front. The direction and force of these various water streams is such as to cause the entire mass of clothes within the basket to revolve and to turn and agitate the clothes therein so that they are 60 thoroughly washed.

The basket may be mounted in the tub T, Figure 5, of the washing machine by attaching to the inside of the tub at each end thereof a U-shaped channel member 25. Each of these channel 65 members engages a pinion member 26 which telescopes thereon and these guides are located between adjacent manifolds 27, 28, the whole assembly being held in place between said manifolds by the strips or guides 29, 30 which may be 70 welded to the manifolds as shown in Figure 8. This arrangement permits the basket to be lifted bodily as by means of the block and fall 31, the hook of which engages a pin 32 which extends between two angle irons 33, 34, secured to the top

of the tub as shown in Figures 2, 3, 4 and 5. Instead of this, any suitable arrangement located either inside or outside the washing machine tub can be employed for raising the basket above the upper edge of the tub, so that clothes may be 5 placed in the basket or removed therefrom.

It will be seen that when the basket is raised from the tub that the outer imperforate surface of the manifolds prevent the water from squirting out through the small perforations 11 all over 10 the surface of the basket, which small streams of water would extend over outside the washing machine tub. The presence of the manifolds prevents this occurrence as there are no apertures near the bottom of the basket except those 15 shown at 24 through which water can extend horizontally, it is sufficient to pull the basket part way out of the tub, let it drain for a moment, then lift it all the way out of emptying and filling 20 position.

Because the basket is perforated all around, it drains instantly and by letting it hang suspended for a few moments, the weight of the clothes on themselves bring about a draining action. Such 25 draining action is obviously not present in any form of basket having solid interior walls merely provided with the water circulating apertures such as 22 and 24. The presence of the additional perforations 11 therefore not only increase the 30 free circulation during the washing period, but also secure rapid draining.

What is claimed is:

1. A washing machine basket having perforated bottom and outer side walls and a plurality of manifolds having imperforate outer walls overlying said perforated outer side walls, said manifolds being open at their bottoms to permit the free escape of liquid therefrom.

2. A washing machine basket comprising an inner lining, a plurality of vertical U-shaped manifolds secured to the outer side walls thereof, said walls being perforated between the legs of each manifold to permit liquid to flow from the interior of said basket into said manifolds.

3. The basket as claimed in claim 2 wherein the bottom of the basket is perforated with rows of perforations and is stiffened by transverse members overlying the outside of said bottom between said rows of perforations.

4. In a washing machine, in combination with 50 a tub, a basket located in said tub, said basket having smooth interior walls and a plurality of apertures therein permitting free circulation of water therethrough, and said walls having additional smaller apertures therein, and a plurality 55 of hollow manifolds overlying said last apertures and having their lower ends discharging outside and below the bottom of the basket.

5. The combination as claimed in claim 4 wherein one side of said basket overlaid with 60 manifolds as claimed, is hinged to permit the contents of said basket to be removed through said hinged side.

6. A basket for a washing machine comprising a rectangular receptacle having smooth inner 65 walls, a plurality of vertical ducts having flat flanged portions thereon spacing said ducts apart and lying in contact with the outside of said wall, said walls being perforated where they overlie the interior of said ducts.

7. The combination as claimed in claim 4 wherein one of the walls of the basket together with said manifolds thereon is hinged to permit the contents of the basket to be dumped.

OTTO T. DEHLE.
